UNITED STATES PATENT OFFICE.

JOSEPH C. DONNELLY, OF BARBERTON, OHIO, ASSIGNOR TO THE DIAMOND MATCH COMPANY, OF CHICAGO, ILLINOIS, A CORPORATION OF ILLINOIS.

MACHINE FOR MAKING MATCH BOOKS.

Application filed December 17, 1926. Serial No. 155,384.

This invention relates to machines for making match books, and particularly to mechanism whereby relatively long strips of matches are positioned in co-operative relation to cutting instrumentalities effective to sever the strips into cards of matches of proper size for match books preparatory to the association of the cards with match book covers.

10 The present invention is especially, though not exclusively, designed for use in connection with, or as an attachment for, the machine for making match books described in Letters Patent of the United States No. 1,042,472, dated October 29, 1912, to M. Paridon and T. A. Palmer, which machine includes an endless carrier; suitable means for placing match book covers thereon; a feed table for pairs of superposed match strips; 20 strip positioning means to which the match strips are manually fed from the table, which means is operative to position the strips adjacent to and longitudinally of the carrier; cutter mechanism for transversely severing the margins of the thus positioned strips to produce match cards, and means whereby the cards are entered in the carrier and associated with covers previously supplied thereto.

30 The object of my invention is to provide novel mechanism whereby the match strips are automatically fed to the machine in a rapid and efficient manner; and to this end the invention, generally stated, comprises 35 means for successively transferring match strips or pairs of strips through a horizontal arc to the strip positioning devices, and means for supplying the match strips or pairs of strips to the transfer means.

40 In the preferred form of my invention herein illustrated, the transfer means comprises an oscillatory element which in each reciprocation thereof engages two strips, or 45 two pairs of associated strips, and places them in proper spaced-relation for engagement by the strip-positioning device, and the strip-supplying means comprises an elongated magazine which is so constructed and located that it can be conveniently supplied 50 with match strips by an attendant, and which

magazine ensures a constant delivery of the strips in proper flatwise position to the transfer means.

The invention also comprises novel features of construction and combinations of parts which will be hereinafter described and claimed.

In the drawings—

Figure 1 is a plan of a portion of a match book machine equipped with match strip feeding mechanism embodying my invention.

Fig. 2 is a front elevation of the same, parts of the hopper being broken away to expose the match strips therein.

Fig. 3 is a transverse vertical section of the machine, as on the line 3—3 of Fig. 2.

Fig. 4 is a plan of the feed table and adjuncts, the strip magazine being omitted and the oscillatory strip transfer element being shown in the feeding position opposite to that shown in Fig. 1.

Fig. 5 is a transverse vertical section, as on the line 5—5 of Fig. 4.

Figs. 6 and 7 are sections through the strip magazine, as on the lines 6—6 and 7—7, respectively, of Fig. 2.

Fig. 8 is a skeleton perspective view of the strip positioning and card setting plungers, and adjuncts.

Fig. 9 is a perspective view of the card setting plunger.

Fig. 10 is a similar view, partly in section, of the feed-table, and associated parts, including the strip magazine.

Fig. 11 is a perspective view of the oscillatory strip-transfer element, and connections therefor.

Fig. 12 is a section through one edge portion of the transfer element and the adjacent hinged wing member thereof, which member is shown positioned beneath the strip-magazine.

Referring to the drawings, 10 designates a suitable supporting frame, including a table 11 upon and along which is guided the upper run of an endless carrier comprising a chain of links 12, whereof each is constructed to receive and support a match book cover, as 13, and a match card or cards, as 14. At a station of the machine cover blanks, each 100

folded at one end, are inserted in the adjacent links of the carrier, and at a succeeding station match strips, as 15, heads outward, are fed to a path in which are included cutters that divide the strips into successive card sections, each section when cut being placed in the carrier and associated with a cover.

The chain is intermittently driven by suitable mechanism comprising, in the present instance, a gear wheel 16 in mesh with rack teeth 17 on the links. The stud shaft of the gear wheel 16 bears a pinion 18 in mesh with the gear face of a pin wheel 19 on a lower stud shaft 20, the pins of which wheel 19 contact with a suitable cam 21 on the main shaft 22 of the machine.

A strip positioning plunger 23, which is guided on a forward extension 24 of the table, is connected at its respective ends by means of links 25 with two arms 26 loosely mounted on a shaft 27 fixed in brackets depending from the table. One of the arms is connected by means of a link 28 with a rock arm 29 which is loosely mounted on the drive shaft 22. On this arm is a roller 30 which engages a face cam 31 on a longitudinal shaft 32 beneath the table. This shaft 32 is driven from the shaft 22 through co-acting gear wheels on the respective shafts. The plunger 23 is held yieldingly in its rearward position by means of a spring 33 which is secured to one of the arms 26 and to the table 11; and the contour of the cam is such that at the proper time the plunger 23 is retracted thereby. A cover plate 34, constituting a supplemental or feed table, overlies the path of the plunger 23, in spaced relation to the carrier, so that when the plunger is in its rearward position match strips can be placed flatwise thereon and rearwardly of the table 34. This done, when the plunger 23 travels beneath such table and away from the match strips, the strips fall upon the main table 11, whereupon in the next succeeding active stroke of the plunger 23, the opposing strips are pushed toward the carrier and positioned on the table 11 with their margins adjacent to and longitudinally of the carrier and below the spaced-apart vertically reciprocating cutters 35 of the cutting mechanism.

The cutters are constructed and operated to sever the margins of the match strips to produce match cards of proper length, which cards as they are cut are pushed to and centrally of covers in the carrier by means of a supplemental bifurcated plunger 36 reciprocating transversely of the main table. This card setting plunger 36 is connected to a slide-plate 37 which is mounted within the feed-table and is connected through a link 38 with the upper arm of a lever 39 loosely mounted on the shaft 27. The lower arm 40 of the lever is connected by means of a link

40 with a rock-arm 41 pivoted on a bracket 42 on the base of the supporting frame. On this rock-arm 41 is a roll 44 which engages a face cam 45 on the drive shaft 22, the contour of the cam groove being such as to effect the timely reciprocation of the card setting plunger 36. 70

The match strips when they are positioned adjacent the carrier by the plunger 36 are advanced at intervals longitudinally of the carrier and beneath the respective cutters preparatory to the cutting of succeeding cards from the strips, all as fully shown and described in Letters Patent No. 1,042,472 aforesaid. 75

According to my invention I provide strip-supplying means whereby match strips are arranged flatwise above the table 34 in a position longitudinally and medially of the path of the strip positioning plunger 23, 80 and I also provide oscillatory transfer mechanism operative to engage the strips thus arranged and deliver them in alternate succession to such positioning plunger. 85

In the machine herein illustrated two separate match strips in spaced endwise relation, or two similarly spaced pairs of superposed match strips, are simultaneously delivered by the plunger 36 to the paths in which the cutting of the strips is effected, 90 and hence the transfer mechanism is constructed and operated to feed the plural strips or pairs of strips in proper relation to the plunger. 95

The strip supplying means preferably 100 comprises a trough-like magazine of novel construction, including a basal structure adapted to locate superimposed match strips in proper position above the table 34. This structure is composed of two end sections 105 suitably spaced from each other and supported somewhat above the top of the table 34; each section having parallel side walls 46, an outer end wall 47, and a projecting flange 48. The flange 48 of one of the sections is bolted to a flange 49 on a curved guide rail 50 (hereinafter described) on the top of the table 34, and the flange 48 of the other section is bolted to a projection 51 from the housing of the cutter head. 110

Rising from the respective basal sections are two corresponding arcuate members 52 constituted by flanges on the inner sides of the curved side members 53 of frame structures 54 which are bolted to suitably-disposed brackets 55 on the table 11. The upper ends of these structures 54 are preferably connected by a cross-bar 54', and the outer edges of the side members 53 have secured thereto flange strips 56 which are concentric with and overhang the members 52, so as to afford curved guide channels for the passage of the match strips to the basal portion of the magazine. Supported on the side structures 54 is the inner end of a 125 130

- trough structure comprising two long guide rails 57 which are spaced apart correspondingly with the curved guide channels and in substantial parallelism with the upper run 5 of the carrier so as to extend longitudinally of the machine. The outer ends of the rails are connected by a cross-bar 58. These rails are preferably of angle material whereof the inner flanges 59 constitute, in effect, a 10 continuation of the respective arcuate members 52, so that match strips supported on their long edges on the flanges 59 and advanced therealong toward the curved channels will enter the channels and pass to the 15 basal sections of the magazine, such strips being gradually turned from their edgewise position to a horizontal or flat position as they progress down the curved channel, as illustrated.
- 20 In order to ensure the passage of the match strips along the magazine, the upper runs of two endless belts 60 are arranged to travel on the respective flanges of the side rails and frame structures, which belts pass 25 about pulleys 61 mounted on shafts 62 suitably supported at the respective ends of the magazine. The belts are flexed over pulleys 63 mounted on a shaft 64 which has its bearings in the side frames 54 and is provided 30 with a pulley 65 which is actuated by a suitable power driven belt 66. The feed belts 60 are maintained in operative frictional contact with the pulleys 63 by means of idlers 67 carried by arms 68 hung on a shaft supported by and between the frames 54 so that when the pulleys 63 are impelled by the driven shaft 64, the feed belts are 35 concurrently driven to effect the feeding of the match strips along the magazine.
- 40 The match strips are supplied to and supported in the magazine in pairs, with the heads of the matches of alternate pairs in reverse position, that is, the heads of the matches of one pair point upward and the 45 heads of the next adjacent pair point downward, and so on in alternate succession, as illustrated in Fig. 2. This alternate disposition of the tapering or wedge-like strips not only enables their compact arrangement 50 in the magazine, but it ensures the proper location of the heads of the succeeding lowermost pairs of strips in the basal portion of the magazine in order to permit their proper transference to the positioning 55 plunger 23.
- 60 In order to present the match strips in an orderly manner to the curved section of the magazine, so that they will be accurately positioned on the transfer mechanism hereinafter described, I provide simple and efficient strip-evening means which effects the "patting" of the ends and tops of the progressing match strips contained in the horizontal trough structure.
- 65 The preferred form of strip-evening

means herein illustrated is of the following construction: 680 designates a cross-shaft having its bearings in brackets 681 depending from the rails 57 of the trough structure, which shaft has fast thereon a sprocket wheel 682 that is continuously driven from a suitable source. Fast on the shaft are appropriate disk cams 683, 684 which in their rotation effect through suitable connections the periodical vibration of evening devices 70 that respectively act against the ends and tops of the match strips contained in the trough structure. 75

The top evener comprises two bars 685 which are mounted on and parallel with the side rails 57. The upper edges of the bars rise above the side rails and extend well along the trough, terminating at the curved portion of the latter, as seen in Fig. 2. The opposite ends of the bars are pivoted, 80 as at 686, to the respective rails, so as to have capacity for limited vertical vibration. The bars are also provided with suitably-disposed rolls 687 which overlie the respective disk cams 683 and are operable thereby 85 to effect the vibration of the bars. Fastened to the free ends of the bars by means, for example, of angle pieces 688 is a plate 689 which extends transversely of the trough, and which plate is provided at its under 90 side with a strip 690 of leather, or other suitable yielding substance, adapted during the vibration of the bars to come in contact with the heads and upper edges of the match strips, thus pressing the raised match strips, if any, uniformly down to the belts 60. (See Fig. 7.) The height of the side rails of the trough above the belts 60 is a trifle in excess of the height of the match strips, so that the evening strip 690 in its 95 downward movement strikes the tops of the rails, thus preventing the crushing of the match heads when the match strips are pressed to a uniform level. 100

The cams 683 which actuate the bars 685 have slight clearance from the rolls 687 when the bars are down, thus permitting the yielding evening strip 690 to rest upon the sides of the trough. 110

The side evener, which acts upon the ends of the match strips, comprises two horizontal bars 691 which are concurrently movable transversely of the trough in longitudinal slots 692 formed in the respective side rails 57 adjacent the curved section. These bars are pivotally supported by arms 693 fast on and rising from lower longitudinal rock-shafts 694 having their bearings in brackets 695 depending from the respective rails 57. The shafts 694 extend adjacent the cross-shaft 680, and are provided with inwardly extending arms 696 having at their inner or free ends pendant fingers 697 that are yieldingly held in operative contact with the respective cams 684 by means of suitably 120 125 130

disposed springs 698. The fingers 697 are preferably adjustably secured to the arms 696 by screws 699. The cams 684 in their rotation actuate the respective fingers and their associated arm and lever connections in a manner to effect the positive outward movement of the vibratory side bars 691, and at an interval in the rotation of the cams, they permit the springs to shift said connections in a manner to move the bars 691 yieldingly inward and against the opposing ends of the match strips contained in the trough, thereby effectually evening the ends of the strips without liability of crushing them.

The strip transfer mechanism, in its preferred construction, includes an oscillatory horizontally-disposed plate 69 of substantially quadrantal form mounted above the table 34 and movable thereon through an arc of 90° so as to pass beneath and constitute a bottom for the open basal structure of the magazine, the angularly disposed edges 70 of the plate being offset in relation to the axis of the plate so that when the plate, in either stroke thereof, is swung to its limit below and beyond the magazine the leading edge of the plate is located at and parallel with the rearward edge of the table 34 while the other edge of the plate is at and parallel with the adjacent side of the throat or space at the bottom of the magazine, as seen in Fig. 4. Any suitable means for actuating the plate 69 may be employed. In the present instance the plate is fast on a suitably-disposed vertical shaft 71 having its bearings in a bracket 72 depending from the forward extension 24 of the table 11, and also in the projection 51 of the cutter housing. (See Fig. 3). Fast on the shaft 71 is a gear 73 with which meshes a horizontal rack 74 slidably mounted in a guide extension 75 of the bracket 72 and provided with a roll 76 in engagement with the peripheral groove of a cam 77 on the main shaft 22 of the machine. The contour of the cam groove is such that the rack is longitudinally reciprocated within limits in a manner to oscillate the gear 73 and its shaft 71 through an arc of 90°, thereby correspondingly actuating the quadrantal transfer plate 69.

Suitably hinged to the plate 69, adjacent its respective edges 70 are outwardly extending wings 78 constituting shelves. The leading wing as it approaches the delivery portion of the magazine is temporarily raised to an inclined position and is thus maintained until it passes under and somewhat beyond the bottom of the magazine. As it continues its travel toward the rear of the table the wing resumes its normal or horizontal position. When the inclined wing is passing directly beneath the magazine it receives and supports the lowermost pair of match strips in the magazine, the

heads of the matches of such strips being at the lower or pivotal end of the wing and in contact with the proximate edge 70 of the plate, as illustrated in Fig. 12. As the plate continues its travel toward the rear of the table 34 the then lowermost strips in the basal structure of the magazine rest on the upper surface of the moving plate, and the strips previously imposed on the leading wing are carried to and positioned above the plunger 23, such wing during its travel resuming its normal or horizontal position to facilitate the discharge of the match strips therefrom and upon the plunger 23 during the next return stroke of the transfer plate. When the leading wing reaches its limit of movement at the rear of the table 34 the other or trailing wing is positioned beneath the magazine, and the then lowermost pair of match strips in the basal structure of the magazine are imposed on the latter wing, which latter wing is now in inclined position to accommodate the heads of the matches. In the next succeeding stroke of the transfer plate, the match strips imposed on such latter wing are carried beyond the rear of the table 34 and above the adjacent surface of the plunger 23, such wing in its travel being lowered in the same manner as described with respect to the other wing. Hence, during each reciprocation (two strokes) of the plate 69, two pairs of match strips are transferred from the magazine to the respective legs of the positioning plunger 23 preparatory to the delivery of the strips by the plunger to the respective paths in which the cutting is effected; one pair of strips being swung through an arc of 90° from one side of the magazine outlet and the other being swung through a similar arc from the opposite side of the outlet. In this way two pairs of strips, heads forward, are accurately positioned upon the respective legs of the plunger 23. Fast on the table 34 is the segmental rail 50 previously referred to, which rail is suitably arranged to afford a guide and guard member for the outer ends of the match strips as they are being swung from the respective sides of the magazine to the rear of the table 34.

As a simple and efficient means to accomplish the periodical vertical movement of the wings 78 during the oscillation of the plate 69, each of the wings is provided on its under side with a projection 79 which, when the wing is in horizontal position, rides on the top of the table 34. A horizontal segmental track 80 having beveled ends 81 is supported on the table 34 beneath the delivery portion of the magazine and in the path of the wing projections during the oscillation of the plate 69, and hence as the plate is swung toward and from the respective sides of the magazine the projections ride upon the track, and the wings are

thereby properly actuated and positioned as previously described. A suitably-disposed stop lug 81' on the pivoted portion of each wing abuts against an adjacent shoulder on the plate and limits the downward movement of the wing to a horizontal plane when the wing is beyond the rear edge of the table 34.

To ensure the discharge of the match strips from the respective wings and upon the positioning plunger 23, during the initial retrograde movements of the transfer plate, suitable stripper and back stop devices for the strips are provided. Preferably these devices comprise two pairs of vertically movable dogs 82, 83 arranged to overhang the rear of the table 34. The outer dog 82 of each pair consists of an arm pivoted at 84 to a lug 85 on the adjacent inner end of the rail 50 and provided with an inclined nose portion 86 which rests by gravity upon the table and lies in the path of the outer end portions of the match strips as they approach and are being moved beyond the rear of the table 34. When the strips are thus being moved the nose of the dog rides lightly upon the tops of the strips, and as the strips escape the table such nose drops in front of the match heads and serves as an effective stripper and back stop for the outer end portions of the match strips.

The inner dog 83 of each pair comprises a movable arm which overhangs the path of the wing above the plunger 23 and is supported at its rear end by a block 87 pivoted to a lug 89 on the projection 51 from the cutter housing. The forward end of the arm is bent downward to form a hook 90 which overhangs the rear of the table, and the edge of the plate 69 is suitably notched, as at 91, to permit the movement of the hook to a position directly in front of the match heads when the strips are located above the positioning plunger 23 by the leading wing 78. Secured to the pivoted block is the rear end of a forwardly extending arm 92 which is provided at its free end with a toe 94 in the path of a cam 95 on the hub 96 of the plate 69, which cam is adapted to co-operate with the toe 94 to effect the timed oscillation of the associated block 87 and dog 83 during the travel of the transfer plate.

The cam 95 preferably comprises a vibratory segmental member pivoted at one end, as at 97, to the plate hub 96, and having an inclined or beveled free end, as at 98 which normally rests upon the neck of the plate. The cam is so located in relation to the toe 94 of the arm 92 that in each partial rotation of the cam the free end thereof rides under the toe and, in consequence, the arm 92 is raised and maintained in that position until the pivoted end of the cam escapes the toe,

whereupon the arm, together with the block 87 and its dog 83, drop by gravity. During the period that the arm 92 is held in raised position by the cam, the match strips on the leading wing of the plate 69 are advanced beneath the raised hook end of the dog and beyond the rear of the table, and hence the hook is permitted to position itself in front of the match heads. In the initial reverse movement of the plate 69 the toe of the arm 92 rides on the neck of the plate below the cam, the free end of the latter passing over the toe and dropping in readiness for a succeeding operation upon the toe. The cams for actuating the respective dogs 83 are constructed and arranged to operate in timed relation to the succeeding transfer stroke of the plate 69 so that as the strips, (or paired strips) are alternately positioned at the rear of the table 34 and upon the respective legs of the plunger 23, the hooks of such dogs 85 are caused to position themselves in front of the heads of the adjacent match strips.

From the foregoing it will be seen that an elongated magazine of large capacity for match strips is provided, and that during the operation of the machine it is merely necessary for the attendant to replenish the magazine from time to time as its contents are reduced by the action of the transfer element. The location of the magazine above the table 34 and its extension longitudinally of the machine facilitates the introduction of the strips in the receiving end of the magazine by the attendant, and it also permits their ready inspection by him during the operation of the machine. Moreover, the described magazine ensures the delivery of the match strips in proper flatwise position for effective engagement by the transfer element in each succeeding stroke. This transfer element is simple in construction and efficient in its operation, since its motion is one of oscillation, and since in each reciprocation it removes two strips, or two pairs of strips, from the magazine and places them in proper spaced relation for engagement by the strip-positioning plunger.

The operation of the mechanism hereinbefore described may be summarized as follows: Assuming the trough-like magazine to be supplied at its receiving end with vertically-disposed match strips, whereof the heads of alternate pairs are in reverse relation, said strips are progressively advanced along the magazine and into the downwardly curved portion thereof by the travelling feed belts 60, the strips as they approach this curved portion being orderly arranged by the actions of the co-operating evener devices against the heads and ends of the strips. In their progress through the curved portion of the magazine the match strips are gradually inclined until they as-

sume a horizontal position immediately above the path of the oscillatory transfer plate 69 and its respective hinged wings or shelves 71. In each stroke of this plate the 5 leading wing or shelf passes directly beneath the magazine and receives and supports the lowermost pairs of match strips, the wing at this stage being inclined to accommodate the heads of the matches. The wing carries 10 the match strips superposed thereon to the rear of the feed table 34 and positions them above the horizontally reciprocating plunger 23, said wing during its rearward travel being caused to resume its horizontal position. 15 In such rearward travel the then lowermost oppositely-pointing pair of match strips in the magazine rest upon the transfer plate 69, so that they are positioned on the other or trailing wing when it is brought 20 beneath the magazine, which latter wing is now in inclined position. In the next following stroke of the transfer plate, the latter wing carries its load to the rear of the feed table 34 and above the plunger 23, the 25 wing being also lowered to horizontal position. In this way, during two consecutive strokes of the transfer plate one pair of match strips are carried from one side of the magazine outlet and another pair from 30 the opposite side, and such pairs of match strips, heads forward, are positioned upon the respective legs of the plunger 23. This done, the plunger 23 is retracted, thus permitting the match strips to fall upon the 35 main table, 11, whereupon in the next forward stroke of the plunger 23 the match strips are accurately positioned with their margins adjacent and longitudinally of the carrier 12 and in close relation to the path 40 of the spaced-apart vertically reciprocating cutters 35 of the cutting mechanism. Such match strips are intermittently advanced longitudinally so as to lie beneath the cutters to the end that succeeding lengths suitable 45 for match cards will be severed from each pair of match strips, which cards as they are produced are entered in the carrier and associated with the covers previously supplied thereto, as fully set out in Patent 50 No. 1,042,472 aforesaid.

As previously mentioned the curved rail 50 on the table 34 serves as a guide for the outer ends of the match strips as they are being transferred from the magazine to the 55 rear of the table 34, and the vertically-movable dogs 82, 83 are periodically operated to ensure the discharge of the match strips from the respective wings of the transfer plate and upon the positioning plunger 23 during the initial retrograde movements of 60 said plate.

It is to be understood that my invention is not limited to the particular construction and organization herein disclosed, as the 65 mechanism may be modified within the prin-

ciple of the invention and the scope of the appended claims.

I claim—

1. In a match-book machine having match strip cutting means, means for positioning match strips adjacent the cutting path, an oscillatory transfer element for moving match strips in flatwise condition through a horizontal arc to the positioning means, means for supplying match strips successively to said element, and means for operating said element in timed relation to the operation of the said positioning means. 75

2. In a match-book machine having match strip cutting means, means for positioning match strips adjacent the cutting path, an oscillatory transfer element for moving match strips in flatwise condition through a horizontal arc to the positioning means, a strip-containing magazine overhanging the 80 path of, and effective to deliver match strips successively to said element, and means for operating said element in timed relation to the operation of the said positioning means. 85

3. In a match-book machine having match strip cutting means, means for positioning match strips adjacent the cutting path, a magazine for a pile of flatwise-disposed match strips, an oscillatory element movable beneath the magazine and comprising a 90 member adapted to sustain the pile and a member adapted to receive the lowermost strips of the pile and transfer them through a horizontal arc to the positioning means, means for operating said element in timed 95 relation to the operation of said positioning means, and means for preventing retrograde movement of the match strips when they are located at the positioning means. 100

4. In a match-book machine having match strip cutting means, means for positioning match strips adjacent the cutting path, a magazine for a pile of flatwise-disposed match strips, an oscillatory member movable beneath the magazine and comprising a 105 member adapted to sustain the pile and a member adapted to receive the lowermost strips of the pile and transfer them through a horizontal arc to the positioning means, means for temporarily tilting 110 said latter member to accommodate the form of the match strips thereon, means for operating said element in timed relation to the operation of said positioning means, and means for preventing retrograde movement of the match strips when they are located at the positioning means. 115

5. In a match-book machine having match strip cutting means, a strip-positioning plunger, means for reciprocating said plunger to position match strips adjacent the cutting path, an oscillatory transfer element for supporting match strips in flat position and moving them through a horizontal arc to a position at and transversely of the ac- 125

130

tive end of the plunger, means for supplying match strips to said element, and means for operating said element in timed relation to the movements of the plunger.

5 6. In a match-book machine having match strip cutting means, a strip-positioning plunger, means for reciprocating said plunger to position match strips adjacent the cutting path, an oscillatory transfer element 10 for supporting match strips in flatwise condition and moving them through a horizontal arc to a position at and transversely of the active end of the plunger, a strip-containing magazine structure overhanging 15 the path of and operative to deliver match strips successively to said element, and means for operating said element in timed relation to the movements of the plunger.

20 7. In a match-book machine having match strip cutting means, a strip-positioning plunger, means for reciprocating said plunger to position match strips adjacent the cutting path, an oscillatory transfer element having a member adapted to receive match 25 strips flatwise and move them through a horizontal arc to a position at and transversely of the active end of the plunger, means for supplying match strips to said member, means for operating said element in 30 timed relation to the movements of the plunger, and means for preventing retrograde movement of the match strips when they are positioned at the plunger.

35 8. In a match-book machine having match strip cutting means, a strip-positioning plunger, means for reciprocating said plunger to position match strips adjacent the cutting path, an oscillatory transfer element having a tiltable member adapted to 40 receive match cards flatwise and move them through a horizontal arc to a position at and transversely of the active end of the plunger, means for temporarily tilting said member, means for supplying match strips to 45 said member when it is in tilted position, means for operating said transfer element in timed relation to the movements of the plunger, and means for preventing retrograde movement of the match strips when 50 they are positioned at the plunger.

55 9. In a match-book machine having spaced-apart match strip cutters, means for positioning match strips adjacent the respective cutting paths, an oscillatory transfer element for moving match strips to the 60 positioning means and in spaced endwise relation to each other, and means for supplying match strips flatwise to said element and in a plane intersecting its path of travel, whereby in each reciprocation of the said member match strips are oppositely engaged thereby and bodily positioned at the respective locations for engagement by the positioning means.

65 10. In a match-book machine having

spaced-apart match strip cutters, means for positioning match strips adjacent the respective cutting paths, an oscillatory transfer element for moving match strips to the positioning means and in spaced endwise relation to each other, a strip-containing magazine overhanging the path of, and effective to supply match strips flatwise to said element and in a plane intersecting its path of travel, whereby in every two strokes of the 75 said element match strips are engaged thereby at the opposite sides of the magazine and bodily positioned at the respective locations for engagement by the positioning means.

80 11. In a match-book machine having spaced-apart match strip cutters, means for positioning match strips adjacent the respective cutting paths, an oscillatory transfer element for moving match strips to the positioning means and in spaced endwise 85 relation to each other, a strip containing magazine comprising an elongated trough-like portion terminating in a delivery portion which overhangs the path of, and is effective to supply match strips flatwise to 90 said element and in a plane intersecting its path of travel, whereby in every two strokes of the said element match strips are engaged thereby at the opposite sides of the delivery portion of the magazine and bodily positioned at the respective locations for engagement by the positioning means.

95 12. In a match-book machine having spaced-apart match strip cutters, means for positioning match strips adjacent the respective cutting paths, an oscillatory transfer element comprising a member adapted temporarily to sustain a pile of flatwise-disposed match strips, and having substantially radial supporting members adapted to 100 receive the alternate lowermost strips of the pile and transfer them to the positioning means, and in spaced relation to each other, and means for sustaining a pile of match strips and supplying them successively to 105 said element in a plane intersecting the path of travel of the said supporting members.

110 13. In a match-book machine having spaced-apart match strip cutters, means for positioning match strips adjacent the respective cutting paths, an oscillatory transfer element comprising a member adapted temporarily to sustain a pile of flatwise-disposed match strips, and having substantially radial supporting members adapted to 115 receive the alternate lowermost strips of the pile and transfer them to the positioning means, and in spaced relation to each other, means for discharging the match strips from each supporting member when it is located at the positioning means, and means for sustaining a pile of match strips and supplying them successively to said element in a plane intersecting the path of travel of the said supporting members.

14. In a match-book machine having spaced-apart match strip cutters, means for positioning match strips adjacent the respective cutting paths, an oscillatory transfer element comprising a member adapted temporarily to sustain a pile of flatwise-disposed match strips, and having substantially radial members tiltably mounted thereon and adapted to receive the alternate lowermost strips of the pile and move them to the positioning means and in spaced relation to each other, means for temporarily tilting the respective supporting members to accommodate the form of the match strips thereon, and means for sustaining the pile of match strips and supplying them successively to said element in a plane intersecting the path of travel of the said supporting members.
15. In a match-book machine having spaced-apart match strip cutters, means for positioning match strips adjacent the respective cutting paths, an oscillatory transfer element comprising a member adapted temporarily to sustain a pile of flatwise-disposed match strips, and having substantially radial members tiltably mounted thereon and adapted to receive the alternate lowermost strips of the pile and move them to the positioning means and in spaced relation to each other, means for temporarily tilting the respective supporting members to accommodate the form of the match strips thereon, means for preventing retrograde movement of the match strips when they are located at the positioning means, and means for sustaining the pile of match strips and supplying them successively to said element in a plane intersecting the path of travel of the said supporting members.
16. In means for feeding match strips, the combination with a magazine for a pile of flatwise-disposed match strips, of an oscillatory transfer element movable through a horizontal path directly beneath the magazine to afford a support for the contained strips, said element having oppositely-acting strip-moving portions which during each reciprocation of said element act in alternation upon the lowermost strips in the magazine and transfer them to positions in which the strips are in spaced endwise relation to each other.
17. In means for feeding match strips, the combination with a magazine for a pile of flatwise-disposed match strips, of an oscillatory transfer element movable through a horizontal path directly beneath the magazine to afford a support for the contained strips, said element having oppositely-acting strip-moving portions which during each reciprocation of the said element act in alternation upon the lowermost strips in the magazine and transfer them to positions in which the strips are in spaced endwise relation to each other, and means for preventing retrograde movement of the strips with the oscillating element.
18. In means for feeding match strips, an oscillatory transfer element for moving the strips through a horizontal arc, said element comprising a substantially quadrantal member having oppositely-acting substantially radial strip-moving portions adapted to receive flatwise-disposed match strips in a plane midway between the limits of travel of the said element, and means at such limits for engaging said strips and preventing their retrograde movement with the oscillating element.
19. In means for feeding match strips, an oscillatory transfer element for moving the strips through a horizontal arc, said element comprising a substantially quadrantal member having oppositely-acting substantially radial strip-moving portions adapted to receive flatwise-disposed match strips in a plane midway between the limits of travel of the said element, and means at such limits for engaging said strips and preventing their retrograde movement with the oscillating element, said last-named means including dog devices and means for actuating said dog devices in timed relation to the travel of the oscillatory element.
20. The combination of an elongated trough structure adapted to support match strips in close lateral relation, a vibratory evening member extending transversely of the structure and operable to pat the tops of the match strips, means for actuating said member, vibratory evening members arranged at the sides of the structure and operable to pat the ends of the match strips, and means for actuating the latter members.
21. The combination of an elongated trough structure adapted to support match strips in close lateral relation, a vibratory evening member, including a strip of yielding material extending transversely of the structure and operable to pat the tops of the match strips, means for actuating said member, vibratory evening members arranged at the sides of the structure and operable to pat the ends of the match strips, and means for actuating the latter members.
22. The combination of an elongated trough structure adapted to support match strips in close lateral relation, and a top evener for said strips comprising a pair of pivoted bars at the respective sides of the structure, a cross-piece connecting said bars and overhanging the structure, a strip of yielding substance on the underside of the said cross-piece, and means for vibrating said bars.
23. The combination of an elongated trough structure adapted to support match strips in close lateral relation, a top evener for said strips comprising a pair of pivoted bars at the respective sides of the structure,

a cross-piece connecting said bars and over-hanging the structure, a strip of yielding substance on the underside of the said cross-piece, and means for vibrating said bars, and 5 end eveners for the strips comprising elongated bars arranged at the sides of the structure and movable toward and from the in-

terior of the latter, and means for vibrating said latter bars.

Signed at Barberton, in the county of 10 Summit and State of Ohio, this 15 day of December A. D. 1926.

JOSEPH C. DONNELLY.
